CURB SYRUP SEPARATOR

Charles A. Oleott, West Milford, N. J.

Application April 21, 1945, Serial No. 589,568

12 Claims. (Cl. 210—75)

1

This invention relates to centrifugal machines and more specifically to the separation of different syrups or liquids expelled from the basket of a sugar centrifugal during an operating cycle.

It is an object of this invention to provide improved means for separating the green syrup from the wash syrup in sugar centrifugals.

In the processing of sugar from sugar bearing materials, such as magma and massecuite, the sugar bearing material is introduced into a centrifugal machine comprising a basket suspended from a shaft. Surrounding the basket is a fixed casing, or curb. During the centrifuging process, sugar grains are retained in the basket and liquids from the sugar bearing material are expelled through openings in the basket and strike the inner walls of the curb and flow down its surface to collecting means at the bottom of the casing. These curb liquids are of two general types, (1) that extracted from the wet sugar during the purging step of the centrifuging cycle (known as green syrup) and (2) that resulting from the spraying of a washing liquid against the interior of the walled up sugar in the basket and which is expelled to the surrounding curb (known as wash syrup). In sugar refining it is important to be able to collect the green syrup (with possibly some wash syrup mixed therewith) and the wash syrup alone, separately. This has been accomplished heretofore by providing two annular troughs; one surrounding the other, at the bottom of the casing and by means of suitable deflector plates guide one type of curb syrup into one trough and later guide the second type of syrup into the other. Various forms of deflector means have been used in the past but they have not been entirely satisfactory for one reason or another. Some have had a tendency to stick and thus not operate easily or at the right time while others have required a large amount of apparatus. The present invention in one of its primary aspects relates to the alleviation of these difficulties and disadvantages.

It is another object of this invention to provide novel means for controlling the operation of a movable member for guiding the fluid in a container during one time period to one receptacle and the fluid in this container during a later time period to a second receptacle.

It is a further object of this invention to provide in sugar centrifugals a novel, positive-acting, simple, non-sticking means for controlling the operation of a deflector member for guiding first green syrup and then wash syrup each to its proper collecting means.

2

The foregoing and other objects are attained in accordance with an illustrative embodiment of this invention by providing a heavy ring pivoted at one point thereof for raising and lowering an annular deflector resting at its outer edge on a shelf within the casing and overlying two annular gutters at the bottom of the casing, the raising and lowering taking place at appropriate times in the centrifuging cycle to cause the separation of the wash syrup from the green syrup. When the deflector is in its lower position, the passage for the curb liquid to the outer gutter is closed and this liquid flows to the inner gutter but when the deflector is in its raised position, the passage to the outer gutter is opened and as the curb liquid flows down the inside of the curb it passes directly into the outer gutter and hence cannot reach the inner gutter.

In order to permit ease of inspection, maintenance and replacement, the base of the centrifugal machine is made removable from the curb which is supported from brackets on the side (contrary to the usual practice wherein the curb is supported from the base).

The invention will be more readily understood by referring to the following description taken in connection with the accompanying drawings forming a part thereof, in which:

Fig. 1 is an elevation view, partly in cross-sections taken in planes through lines 1—1 in Fig. 2, of a vertical shaft, suspension-type sugar centrifugal machine including means in accordance with the invention for separating curb syrups or liquids;

Fig. 2 is a plan view of the machine of Fig. 1;

Fig. 3 is a partial cross-sectional elevation view, with portions broken away, of the machine of Fig. 1 taken in a plane through line 3—3 of Fig. 2, the curb syrup separator being shown in the raised position;

Fig. 4 is an elevation view, partially in cross-section taken in a plane through line 4—4 of Fig. 2, of the lower portion of the arrangement of Fig. 1 showing the curb bottom lowered from its normal position; and

Fig. 5 is a detail view of means to prevent the curb syrup separator from rotating.

Referring more specifically to the drawings, Fig. 1 shows, by way of example for illustrative purposes, a sugar centrifugal machine 10 of the vertical-shaft type which is suspended from overhead beams and which machine is provided with novel means in accordance with this invention for controlling the separation of the two general kinds of curb syrups, i. e. green syrup and wash

syrup, and is constructed in such manner that this controlling means is readily accessible in case of repair and replacement.

The centrifugal machine 10 is suspended from a suspension head 11 provided with a pulley 12 which is turned by a belt 13 from any suitable prime mover (not shown). The pulley is attached to a vertical shaft or spindle 14 from which is suspended the usual mesh basket 15 adapted to rotate within a curb or casing 16. Surrounding the spindle 14 is any suitable braking means 17, preferably of the water cooled type.

The curb shell 16 (also see Fig. 2) is supported from the sides by brackets 18 attached to vertical support members 19 which are supported from horizontal beams 20. The bottom casting 21 of the centrifugal machine comprising the annular troughs 22 and 23 and the deflector mechanism to be described hereinafter is supported from the curb shell 16 by means of a plurality of bolts 24 circumferentially arranged around the shell and two or more cap screws 25. In the arrangement shown in the drawings, two diametrically spaced cap screws 25 have been provided. The lower threads of each of these screws 25 are encased in a tube 26 which is enclosed at the lower end and fastened to a nut 27 at the upper end. A hardened steel washer 28 is located under the head of cap screw 25 to prevent wear at this portion of the screw. Turning the cap screws 25 after the bolts 24 have been removed causes the bottom casting 21 to be raised or lowered. Rails 29 are provided under the casting 21 to support it when it is lowered, lugs 30, of which there are preferably four, being provided to hold it in place on the rails. After the cap screws and the various piping and other connections have been removed the bottom casting 21 can be moved on these rails.

The annular gutters 22 and 23 in the bottom casting 21 are separated by an annular vertical partition member 31. Overlying this partition is an annular deflector 32 resting on a shelf 33 at its outer edge and adapted to be raised and lowered. The deflector 32 may overhang the partition 31 as shown in the drawing or it may be made with a labyrinth seal fitting over the partition 31 as in the manner of the member 21 in Patent 728,737, issued May 19, 1903, to James W. Macfarlane, or it may be machined to a syrup tight joint with the partition member as shown in Fig. 4 of Patent 703,728, issued July 1, 1902, to Adolf Holland. The joint 34 between the members 32 and 33 is carefully machined so as to be sufficiently tight against the flow of syrup such as is thrown off from the centrifugal basket 15 during the centrifuging process. Obviously, when the deflector 32 is raised a small amount, such as, for example, one half inch (see the position in Fig. 3), there is an opening at the joint 34 which will permit the wash water from the centrifugal basket to flow down the wall of the curb 16 into the outer gutter 23. When the deflector 32 is lowered to the position shown in Fig. 1, the opening 34 to the outer trough 23 is closed off and the syrup is thus compelled to run over the top of deflector 32 into the inner trough 22.

Troughs 22 and 23 are provided with suitable outlets (not shown). By way of example, these outlets may be similar to those disclosed in Fig. 4 of Holland Patent 703,728, issued July 1, 1902. Likewise there is provided a wash pipe (not shown), which may be of the type shown in this Holland patent, or other means for washing residual syrup off the wall of the curb 16 and

for preventing the accumulation of sugar grains which might prevent tight closing of the joint 34.

In accordance with the invention, there is provided a novel means of raising and lowering the deflector 32 which means will now be described. A heavy ring 35 is supported within trough 23 at one side, by a projection 36 (see Fig. 3) resting in a pocket 37. The pocket 37 is a cavity in the bottom casting 21 and acts as a fulcrum around which the ring 35 can tilt. Diametrically opposite the fulcrum the ring 35 rests on a lever 38 which is securely fastened to a shaft 39 mounted in bearings which may be equipped with stuffing boxes in casting 40. The casting 40 is suitably fastened to the bottom casting 21.

Securely fastened to the shaft 39 but outside the box 40 is a lever 41 connected by a pin to a clevis 42 which in turn is fastened to a connecting rod 43 which at its other end is fastened to a piston 44 in an air cylinder 45, so arranged that the admission of air into the upper part of the cylinder presses the piston down, thus lowering lever 41 and raising lever 38. This has the effect of raising one side of the ring 35. A suitable cylinder of the type herein briefly shown and described is shown and described in greater detail in Olcott Patent 2,254,388, issued September 2, 1941 (see Fig. 3). The cylinder is preferably pivoted at its upper end around pivot 46.

To prevent the ring 35 from rotating due to vibration, the pocket 37 is closed at the ends so that the projection 36 cannot move laterally, and at the other side the partition member 31 has a projection 47 engaging slot 48 in the ring 35. The means for preventing the deflector 32 from rotating is shown in Fig. 5. The screws 49 and 50 project into pockets 52 in projection 53 forming part of ring 35.

It is clear that when the ring 35 is tilted by raising lever 38, it will move upward at all points except at the fulcrum 37. To engage the ring 35, the deflector 32 is provided with the three cap screws 49, 50 and 51 spaced 120 degrees apart (see Fig. 2). The screws 49 and 50 are located 60 degrees each side of fulcrum 37 as shown in Fig. 2 while the third screw 51 is mounted on the deflector 32 directly over the lever 38. It is obvious from Fig. 2 that the distance *d* from the fulcrum 37 to the line through screws 49 and 50 is approximately one fourth of the distance *D* from the fulcrum 37 to the screw 51. Thus if it is desired to raise the deflector 32 by one half inch all around, for example, and the ring 35 is tilted so that the part thereof directly under screws 49 and 50 rises one half inch, then the part of the ring directly under screw 51 will rise two inches. Because of this, screws 49 and 50 are lowered until they almost touch the ring 32 while the screw 51 is adjusted so that there is a clearance, when the deflector 32 is in its closed position, of about one and one-half inches between the bottom of the screw 51 and the top of the ring 35. Thus, in the operation of raising the deflector 32, when it is desired to cause the curb syrup to flow into the outer annular trough 22 at the desired point in the centrifuging cycle, the ring 35 is tilted by raising lever 38, and, at first, ring 35 will engage screws 49 and 50 and with a four to one leverage exert a large amount of pressure to disengage the deflector member 32 from the shelf 33 to which it may adhere due to the stickiness of the syrup. This breaks the joint and the continued tilting of the ring 35 causes it to engage screw 51 by the time screws 49 and 50 have been raised three-eighths of an inch. A

movement of lever 38 amounting to an additional one-half inch rise of the end under the ring 35 raises the screws 49 and 50 and the deflector 32 at that point an additional one-eighth inch. Thus at the end of the raising movement, the deflector 32 is level and the opening at the joint 34 is one-half inch all around. Obviously the dimensions given are merely by way of example and other openings either greater or less than one-half inch may be used.

Principal advantages of the arrangement in accordance with this invention are: (1) there is provided a large leverage and slow motion for breaking the deflector 32 away from its joint with the shelf on which it rests, and a more rapid motion to secure a suitable opening once the joint has been broken; (2) it permits operation from a single point outside the curb and does not require a bail extending around the curb, which is objectionable because it interferes with the installation of other apparatus around the centrifugal; (3) the lifting arrangement shown is less costly to manufacture than other arrangements for this purpose; and (4) the arrangement is such that it is easy to inspect and maintain and to replace parts thereof, this latter being made possible by the easy removal of the bottom casting 21 by merely taking out the bolts 24 and turning the two screws 25 together till the casting 21 rests on the rails 29. After the screws 25 and the pin holding clevis 42 to the lever 41 have been removed and all piping connections to the gutters disconnected, the bottom casting can be moved forward on the rails 29 and inspected and serviced as required.

Although the present invention has been described in terms of an illustrative embodiment, it should be realized that the invention and its several features are susceptible of embodiment in a variety of other forms. Hence the invention is to be understood as comprehending such other forms as may fairly come within the spirit and letter of the appended claims. For example, if the centrifugal shown in the drawings is required for use under conditions where the basket 15 may swing enough to hit the side of the curb, the bottom structure can be located at a lower level so that the tops of screws 49, 50 and 51 clear the bottom of the basket 15. This can be accomplished by making the curb shell larger in the vertical direction. Furthermore, it is obvious that the operation of the separator can be effected by use of other suitable means instead of by the piston and cylinder shown or that the cylinder 45 can be operated by any suitable fluid. Moreover, the control means can be either manual or automatic.

What is claimed is:

1. In a centrifugal machine, a suspended basket adapted to be rotated, a cylindrical curb shell surrounding said basket, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said de-

flecting ring off its seat on said ledge comprising means for applying lifting force first to one part of said deflecting ring to loosen it from said ledge and then, after said deflecting ring has been raised at said one part by a predetermined amount, to another part of said deflecting ring also.

2. In a centrifugal machine, a suspended basket adapted to be rotated, a cylindrical curb shell surrounding said basket, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising a ring member positioned under said deflecting ring and provided at one point on the lower surface thereof with a pivot seated within the confines of the base member, means for applying a lifting force to said ring member at a point substantially diametrically opposite the pivot point, and means for causing said ring member to apply lifting force to said deflecting ring at the portion thereof opposite the pivot point but only 35 after lifting force has been first applied by said ring member to at least one portion of the deflecting ring nearer the pivot point.

3. In a centrifugal machine, a suspended basket adapted to be rotated, a cylindrical curb shell surrounding said basket, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising a ring member positioned under said deflecting ring and provided at one point on the lower surface thereof with a pivot seated within the confines of the base member, means for applying a lifting force to said ring member at a point substantially diametrically opposite the pivot point, and means for causing said ring member to apply lifting force to said deflecting ring at the portion thereof opposite the pivot point but only 55 after lifting force has been first applied by said ring member to at least one portion of the deflecting ring nearer the pivot point, said last-mentioned means comprising a plurality of contact devices depending from said deflecting ring to apply lifting force from said ring member to said deflecting ring, one diametrically opposite the pivot point and at least one other nearer the pivot point, the one device opposite the pivot point being shorter than said one device nearer the pivot point, whereby the one device opposite

the pivot point is contacted by said ring member only after the said other contact device has been contacted thereby.

4. In a centrifugal machine, a suspended basket adapted to be rotated, a cylindrical curb shell surrounding said basket, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising a ring member positioned under said deflecting ring and provided at one point on the lower surface thereof with a pivot seated within the confines of the base member, means for applying a lifting force to said ring member at a point substantially diametrically opposite the pivot point, and means for causing said ring member to apply lifting force to said deflecting ring at the portion thereof opposite the pivot point but only after lifting force has been first applied by said ring member to at least one portion of the deflecting ring nearer the pivot point, said ring member having a protuberance on the lower part thereof which forms the pivot and which is seated within a complementary indentation in the bottom of said outer trough.

5. The combination of elements as in claim 2 in further combination with means to prevent said ring member from rotating.

6. In a centrifugal machine, a suspended basket adapted to be rotated, a cylindrical curb shell surrounding said basket, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising a ring member positioned under said deflecting ring and provided at one point on the lower surface thereof with a pivot seated within the confines of the base member, means for applying a lifting force to said ring member at a point substantially diametrically opposite the pivot point, and means for causing said ring member to apply lifting force to said deflecting ring at the portion thereof opposite the pivot point but only after lifting force has been first applied by said ring member to at least one portion of the deflecting ring nearer the pivot point, said last-mentioned means comprising three screws depending from said deflecting ring and spaced substantially 120 degrees apart, one of said screws being shorter than the other two screws and positioned substantially 180 degrees from the pivot

point, whereby the other two screws are contacted by said ring member before said one screw is contacted thereby.

7. In a centrifugal machine, a suspended basket adapted to be rotated, a cylindrical curb shell surrounding said basket, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising means for applying lifting force first to one part of said deflecting ring to loosen it from said ledge and then, after said deflecting ring has been raised at said one part by a predetermined amount, to another part of said deflecting ring also, all of said lifting force being applied from a single control point outside said centrifugal machine.

8. In a centrifugal machine, a suspended basket adapted to be rotated, a cylindrical curb shell surrounding said casing, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, means for supporting said curb shell from the side thereof so that there is an open space below the bottom of the troughs, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, means for raising said deflecting ring off its seat on said ledge, and means for removably supporting said base member, ledge and deflecting ring from said curb shell, said last-mentioned means comprising a flange outside said curb shell and screw means for bolting said flange to the base member and for allowing said base member to be lowered with respect to said curb shell.

9. A curb for a sugar centrifugal machine comprising a cylindrical curb shell, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising means for ap-

plying lifting force first to one part of said deflecting ring to loosen it from said ledge and then, after said deflecting ring has been raised at said one part by a predetermined amount, to another part of said deflecting ring also.

10. A curb for a sugar centrifugal machine comprising a cylindrical curb shell, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising a ring member positioned under said deflecting ring and provided at one point on the lower surface thereof with a pivot seated within the confines of the base member, means for applying a lifting force to said ring member at a point substantially diametrically opposite the pivot point, and means for causing said ring member to apply lifting force to said deflecting ring at the portion thereof opposite the pivot point but only after lifting force has been first applied by said ring member to at least one portion of the deflecting ring nearer the pivot point.

11. A curb for a sugar centrifugal machine comprising a cylindrical curb shell, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising a ring member positioned under said deflecting ring and provided at one point on the lower surface thereof with a pivot seated within the confines of the base member, means for applying a lifting force to said ring member at a point substantially diametrically opposite the pivot point, and means for causing said ring member to apply lifting force to said deflecting ring at the portion thereof opposite the pivot point but only after lifting force has been first applied by said ring member to at least one portion of the deflecting ring nearer

the pivot point, said last-mentioned means comprising a plurality of contact devices depending from said deflecting ring to apply lifting force from said ring member to said deflecting ring, one diametrically opposite the pivot point and at least one other nearer the pivot point, the one device opposite the pivot point being shorter than said one device nearer the pivot point, whereby the one device opposite the pivot point is contacted by said ring member only after the said other contact device has been contacted thereby.

12. A curb for a sugar centrifugal machine comprising a cylindrical curb shell, a base member including separate inner and outer annular troughs at the bottom of said curb shell for collecting liquid which is expelled from the basket and flows down the inner wall of the shell, said troughs being so positioned with respect to said curb shell that liquid flowing down said shell normally flows into said outer trough only, an annular ledge projecting inwardly from the curb shell above said outer trough, a movable annular deflecting ring seated on said ledge and extending inwardly to a point overlying said troughs in such a manner that when said ring is seated liquid flowing down the curb shell is directed by said deflecting ring into said inner trough, and means for raising said deflecting ring off its seat on said ledge comprising a ring member positioned under said deflecting ring and provided at one point on the lower surface thereof with a pivot seated within the confines of the base member, means for applying a lifting force to said ring member at a point substantially diametrically opposite the pivot point, and means for causing said ring member to apply lifting force to said deflecting ring at the portion thereof opposite the pivot point but only after lifting force has been first applied by said ring member to at least one portion of the deflecting ring nearer the pivot point, said ring member having a protuberance on the lower part thereof which forms the pivot and which is seated within a complementary indentation in the bottom of said outer trough.
